UNITED STATES PATENT OFFICE.

WILLIAM A. MEDLIN, OF RIPLEY, MISSISSIPPI.

RACK.

1,054,228.

Specification of Letters Patent. Patented Feb. 25, 1913.

Application filed July 27, 1912. Serial No. 711,894.

To all whom it may concern:

Be it known that I, WILLIAM A. MEDLIN, a citizen of the United States, residing at Ripley, in the county of Tippah and State of Mississippi, have invented certain new and useful Improvements in Racks, of which the following is a specification, reference being had to the accompanying drawings.

This invention comprehends certain new and useful improvements in racks and relates more particularly to those of the type commonly designated as wall racks which are provided with a plurality of swinging arms.

15 The primary object of the invention is to provide a rack of this nature having horizontally swinging arms which may be adjusted vertically and which will remain in any adjusted position.

20 A still further object of the invention is to provide a rack having arms which may be easily attached or detached from a vertical supporting rod.

Another object of the invention is to provide a device of this nature which shall consist of a small number of parts, which may be cheaply manufactured, and one which will be a general improvement over those now in use.

30 The invention also aims to generally improve devices of this nature, to render them more useful, durable and commercially desirable.

With these and other objects in view, as will become more apparent as the description proceeds, the invention consists in certain novel features of construction and arrangement of parts as I shall hereinafter fully describe and claim.

40 For a complete understanding of my invention, reference is to be had to the following description and accompanying drawings in which,

Figure 1 is a perspective view of my invention. Fig. 2 is a perspective view of one of the arms.

Referring to the drawings by numerals, 1 designates a body member rectangular in shape and made of any suitable material.

50 A supporting strip 2 formed intermediate its ends with a socket 3 is rigidly secured transversely of the body 1. A second supporting strip 4 provided with a circular opening 5 which extends entirely through

the same is secured transversely of the body 55 1 adjacent the upper edge thereof. These strips support in a vertical position, the metallic rod 6 which has its lower end positioned in the socket 3 and which extends upwardly through the opening 5. The vertical rod 6 supports a plurality of swinging arms 7 each of which comprises a strip of flat metal bent downwardly at one end and twisted as at 8 for the purpose of bringing the end portion 9 in a plane at right angles to the main portion of the arm. Each of the end portions 9 is provided with a V shaped end opening notch or recess 10, the walls of which are beveled downwardly and inwardly for the purpose of providing sharpened edges for engagement with the rod 6. In order that the arms 7 may be supported upon the rod 6, I provide each of them with an extension 11 which has its outer end bent to form a hook for engagement with the rod 6.

It will be seen that this construction provides an arm which when attached to the rod 6 will be supported so as to swing horizontally and which may be raised or lowered to any desired position. The leverage produced by the outwardly extending arm causes the beveled walls of the notch 10 to bite into the rod 6, and the greater the weight upon this arm the more tightly will the walls of the notch 10 bind against the rod 6. In order to shift the arm vertically, it is only necessary to grasp the outer end of the same and raise it slightly, which action will cause the walls of the notch 10 to loosen their hold upon the rod after which the arm may be either raised or lowered. To remove the arms 7 from the supporting rod 6 it is only necessary to turn them into a position parallel with the front face of the body 1 after which the hooked extensions 11 may be disengaged from the rod 6 by tilting the arms upwardly.

The free ends of the arms 7 may be formed in various shapes such as the hook 13, and loop 14, for the purpose of supporting objects of different shapes. When in use the rack is secured to a supporting member by suitable fastenings passing through the openings 15 formed in the body 1.

It is to be understood that I do not wish to be limited to the exact construction and arrangement of parts herein shown and de-

scribed but may make such changes as will fall within the scope and spirit of the invention.

What I claim is:—

- 5 A rack of the class described, comprising a body, transverse supporting strips secured in spaced relationship to one face of said body, a vertical rod supported by said strips, an arm horizontally positioned upon said rod, said arm comprising a flat metal strip bent downwardly at one end and twisted so as to bring the extreme end portion of the arm in a plane at right angles to the
- 10

body portion, said end portion being formed with an end opening V shaped notch, the 15 walls of which are beveled downwardly and inwardly and a hooked extension extending longitudinally from the body portion of the arm and adapted to engage the supporting rod at a point above said V shaped notch. 20

In testimony whereof I hereunto affix my signature in the presence of two witnesses.

WILLIAM A. MEDLIN.
